(57) **CLAIM**

The ornamental design for an cloud-shaped gusset, substantially as shown and described.

DESCRIPTION

FIG. 1 is a perspective view of a cloud-shaped gusset of the present invention, as it may be used in an undergarment (the broken lines shown on the cloud-shaped gusset and on the undergarment represent unclaimed features);

FIG. 2 is a plan view of the claimed cloud-shaped gusset design;

FIG. 3 is a front elevational view of the claimed cloud-shaped gusset design;

FIG. 4 is a rear elevational view of the claimed cloud-shaped gusset design; and,

FIG. 5 is a right side elevational view of the claimed cloud-shaped gusset design, (the left side elevation view is a mirror image thereof).
